UNITED STATES PATENT OFFICE.

JAMES C. WOODSON, OF MANSFIELD, OHIO, ASSIGNOR TO WESTINGHOUSE ELECTRIC & MANUFACTURING COMPANY, A CORPORATION OF PENNSYLVANIA.

INCASED HEATING UNIT.

Application filed March 31, 1927. Serial No. 179,730.

My invention relates to electrical heating units and more particularly to incased heating units for outdoor use.

An object of my invention is to provide a relatively simple and easily manufactured incased heating unit.

Another object of my invention is to provide an incased heating unit that shall have a ground terminal associated therewith.

10 In practicing my invention, I provide a tubular casing, removable end closure members therefor, metal strips within the casing extending laterally thereof at the respective ends of the casing, a heating unit embodying 15 a metal supporting member and refractory resistor supports therein together with a resistor, water-tight terminal members for the resistor, and a ground terminal clamped against the outer surface of the casing at one 20 end thereof by the spaced radially-extending water-tight terminal members.

In the drawings,

Figure 1 is a view, in longitudinal section, of a heating unit embodying my invention.

25 Fig. 2 is a view, in lateral section therethrough, taken on the line II-II of Fig. 1, and

Fig. 3 is an end view with a cap member removed therefrom.

30 An electrical heater 11 embodies a tubular metal casing 12 that may be made of steel pipe of some standard size, the two ends thereof being provided with threads to permit of mounting end closure members 13 and 14 thereon.

Two metal strips 15 and 16 are located within the tubular casing adjacent to each end thereof extending laterally of the casing, the two ends of each strip being welded to the 40 inner surface of the casing, as shown more particularly in Figs. 2 and 3 of the drawings.

The strips 15 and 16 serve as supporting members for a heating unit 17 located within the casing and extending longitudinally thereof. The unit 17 comprises a sheet-metal member 18, of substantially overhung-channel shape in lateral section, within which are located a plurality of refractory members 19 which may be relatively short in order to permit of easy manufacture and which are located within the member 18 in end-to-end abutting relation relatively to each other. A plurality of undercut grooves 21 are provided in the respective members 19 in such manner 55 that all of the grooves are aligned longitudinal-

ly of the heating unit to receive a helically wound resistor 22. The number of undercut grooves 21 is even, in order that both the beginning and the end of the resistor member 22 may be located at one end of the heating 60 unit proper.

The heating unit 17 is secured to the strips 15 and 16 by bolts 23 and 24, insulating washers 25 and 26 being provided on each side of the strips 15 and 16, respectively, to provide 65 additional insulation between the resistor 22 and the casing 12. Cooperating nuts and lock washers are mounted on the end of the bolts 23 and 24 to securely clamp the member 18 against the strips 15 and 16. 70

The refractory members 19 are prevented from moving longitudinally of the channel member 18 by washers 27 mounted on the bolt 24 and by an upturned integral portion 28 of the member 18 of channel section, this integral portion being shown at the left-hand end of Fig. 1 of the drawing. 75

The ends of the resistor member 22 are connected to terminals 29 and 30, each of substantially L-shape, one leg of which is clamped 80 against the outer end of a refractory end member 19 by a bolt 31 having a nut 32 cooperating therewith in the usual manner.

An additional nut 33 is provided on the outer end of the bolt 31 in order to permit of 85 securely clamping an end of the resistor 22 against the nut 32, which latter nut is not screwed down tight against the cooperating terminal of L-shape. This is for the reason that some relative expansion will take place 90 between the refractory member 19 and the bolt 31 which might cause breaking of the refractory member if the nut 32 were screwed down tightly.

Water-tight terminal members for the device are provided, each embodying a metal bushing 34 extending radially into the casing at one end thereof and having cooperating screw threads to permit of making a water-tight joint therebetween. A bushing 35 100 of a suitable electric-insulating material, the outer end of which is provided with an annular shoulder, fits into the tubular metal bushing 34, and a metal plug 36, also of tubular shape and having an outer annular shoulder 105 portion, has screw threaded engagement with the metal bushing 34. A conductor 37 extends into the water-tight bushing and has its inner end connected to the outer leg portion of a terminal member by screws 38. 110

- Asbestos string 39 is wound around the conductor 37 before the metal plug 36 is screwed into the bushing 34, the inner end of the plug 36 being of inverted cone shape so that 5 the asbestos string 39 will be compressed, substantially as shown in Fig. 3 of the drawing, to provide an inner water-tight joint.
- A metal strip 41, constituting a name plate and a ground terminal, is securely clamped 10 against the arcuate outer surface of the casing to extend laterally therearound, substantially as shown in Fig. 3 of the drawing. That part of the strip 41 located between the spaced water-tight terminal members 15 may constitute a name plate, while an extending end portion thereof may be provided with a suitable cable terminal 42 to permit of connecting a ground wire thereto in a manner well known in the art.
- 20 In building a heater of this type, a standard pipe may be cut to any desired length, after which the strips 15 and 16 are welded in place from the end openings in the pipe. The previously assembled heating unit 17 25 may then be mounted in proper operative position and held on the strips by the bolts 23 and 24, as hereinbefore described. The watertight terminals and conductor leads are then placed in proper operative positions, the 30 ground terminal strip being clamped against the pipe by them and connections made between the conductors 37 extending through the water-tight terminal members and the terminals 29 and 30 of the heating unit 35 proper. The end closure members 13 and 14

are then mounted in place, being screwed on tightly to make the entire heater watertight.

Various modifications may be made in the device embodying my invention without departing from the spirit and scope thereof, 40 and I desire that only such limitations shall be placed thereon as are imposed by the prior art or are set forth in the appended claims.

I claim as my invention:

1. In an incased heater, the combination 45 with a tubular metal casing, end closure members therefor, a heating unit within said casing and water-proof terminal members at one end of said casing, of a ground terminal member secured against said casing by 50 said terminal members.

2. Means for supporting an electrical-resistance heating element, comprising an elongated member of substantially channel shape in lateral section, a plurality of insulating 55 blocks positioned in said channel, means in the upper faces of said blocks for spacing the convolutions of said heating element, and means for retaining said blocks in said channel in operative relation.

3. In an incased electrical heating element having a terminal projecting through and secured to the casing thereof, means constituting a combined ground terminal and name plate clamped to said casing by said terminal 65 in electrical contact with said casing.

In testimony whereof, I have hereunto subscribed my name this 23 day of March 1927.

JAMES C. WOODSON.
